UNITED STATES PATENT OFFICE.

JOHN BERTRAM MORTON KNUTSEN, OF POTTS POINT, NEAR SYDNEY, NEW SOUTH WALES, AUSTRALIA.

APPARATUS FOR THE CONTROL AND OPERATION OF ELECTRIC LIFTS AND THE LIKE.

Application filed November 23, 1925, Serial No. 70,934, and in Australia May 18, 1925.

This invention relates to electric lifts and the like but more especially refers to the control and regulation of the operation of lift machinery relative to floor landings or other desired points of stopping or control such as overrunning points and the like and it further refers to the control of the opening of doors or gates relative to the position of the lift car or load. The object of the invention is to provide an efficient and accurate means for controlling the various switches, locks and the like which operate and control the doors, the automatic floor levelling and floor setting mechanism, and the overrun limit switches and other well known devices associated with lifts.

A further object is to provide a device for these purposes which shall operate silently and without making actual mechanical contact thus obviating the objectionable clatter and excessive wear associated with present system of control.

A further object is to provide a means of operation which can be easily rendered inoperative at ordinary points or zones of operation when it is so desired.

The invention consists essentially in providing a magnetically operated switch or other device, in the magnetic circuit of which an excessive air gap is formed the device being so arranged that this air gap will be closed or almost wholly closed when it is desired that the device should operate.

When the magnet is energized with the gap open the pull is relatively small causing the switch or other device to remain inoperative, but when the air gap is closed or partially closed the pull is greatly increased thus enabling the switch or device to operate.

The magnetic device may be placed on the lift car or load and is made to move in conformity therewith. At desired points of control the air gap or rather the part of the iron core or magnetic circuit adjacent to the air gap is made to pass close to an iron bar of suitable form adjustably fixed in the well. The air gap is considerably reduced and the magnetic pull greatly increased so that the switch or lock or other mechanism is caused to operate.

It is obvious that no mechanical wear will take place and that no noise other than the very slight knock of the closing switch or other mechanism will be heard.

In the accompanying drawings are shown diagrammatically several applications of the invention but it is to be understood that the invention is not restricted to the forms or for the purposes shown therein.

Figure 1 is a diagrammatic perspective view of apparatus for door locking or like purposes.

Figure 2 is a diagrammatic perspective view of apparatus for the control of automatic floor levelling mechanism or the like.

Figure 3 is a diagrammatic side elevation of a lift car and a floor showing the relative positions of the fixed and moving parts of the apparatus shown in Figure 2, and

Figure 4 is a diagrammatic perspective view of apparatus similar to that shown in Figure 1, but adapted for use on alternating current circuits.

Referring to Figure 1, 5 is an electro-magnet of any well known construction in the magnetic circuit of which is a relatively large air gap. The magnet is mounted on and adapted to move with the lift car (not shown). At suitable positions on the lift well are placed rigid parallel bars 6 of mild steel or other suitable and well known magnetic material arranged to register with the free ends of the core 7 and having their ends or polepieces so disposed as to become adjacent to an armature 8 which is pivoted in any suitable manner. The armature 8 is provided with means such as the arm and pin-connected rod 10 for operating the lock or other mechanism. This mechanism is constructed and operated in well known manner in accordance with well known practice and is so arranged as to keep the armature 8 normally away from the bars 6 either by gravity or by any suitable arrangement of springs or the like.

In Figures 2 and 3 is shown apparatus suitable for controlling the operation of automatic floor levelling mechanism. A frame 11 of non-magnetic material is rigidly attached to the lift car 13 and holds three cores 14, 15, and 16 which project beyond the frame so as to pass close to one or the other of the magnetic metal members 17 and 18 which are adjustably fixed in the lift well. The middle or main core 15 is provided with an electro-magnetic winding 19 and from an extension of this core are pivoted a pair of armatures 12 and 12^a carrying contacts 20 and 21 adapted to register with the sta-

tionary contacts 22 and 23. These pairs of contacts are insulated and mounted in any well known manner while the armatures 12 and 12^a are normally retained in such a manner as to keep the contacts apart. When the winding 19 is energized magnetic circuits through the main core 15, auxiliary cores 14 and 16 and armatures are established but when the lift car is within the range of one or the other of the stationary members 17 or 18, one of the air gaps between 14 and 15 or 15 and 16 is very materially reduced so that one of the pairs of contacts 20—22 or 21—23 is closed owing to the increase of pull on the armature 12 or 12^a corresponding to whichever of the two members 17 and 18 is exerting its influence.

For example, assuming that the lift car is moving downwards and is approaching a floor 24 at which it is desired to stop and the car controller is put at the "off" position for that purpose, the winding 19 is immediately energized and owing to the virtual closing of the air gap 14—15 by the member 17 the armature 12 is attracted to close the contacts 20 and 22 to energize the circuit 25 which operates the automatic floor levelling mechanism to bring the car slowly and accurately to a stop in register with the floor 24, the contacts 20—22 being opened as soon as the bars 14 and 15 pass beyond the end of the member 17 to cut out the floor levelling mechanism and allow the machinery to stop. Should the car and its machinery have energy sufficient to cause it to pass beyond the floor 24 the member 18 will partially close the air gap 15—16 thus causing the contacts 21—23 to close and energize the circuit 26 to operate mechanism 40 of well known type to return the car to the floor 24. On the upward journey the operation of the device would be the same, the necessary reversals being made in the controlling circuits in accordance with adopted practice.

In Figure 4 is shown an arrangement suitable for use on alternating current circuits. It is virtually a transformer in which the primary and secondary windings and their cores are only brought into their correct relative positions when it is desired that the device should operate. The primary winding 27 is energized and as soon as the rigid bars 28 forming part of the magnetic circuit come opposite the members 29 and 30 the magnetic circuit is practically completed and the secondary winding is energized and if this winding is short circuited as at 32 the pull will cause the part 29 of the magnetic circuit to move and operate the bell crank 33 and rod 34 or other device to actuate the required mechanism.

When the two parts of the magnetic circuit become separated, the mechanism would automatically return to normal.

The primary may be carried on the car and a number of secondaries placed in the lift well at points which it would be desired to cause mechanism to operate.

The various windings or the like of the above described devices may only be energized when it is desired that the switch or device shall operate at any particular point. Mechanical wear and consequent noise is thus further eliminated. The means for energizing the coils may be operated by the movement of the car control switch or in any other well known manner.

It will be clearly seen that the principle described above may be utilized for the control of the operation of any mechanism dependent on the position of a lift car or the like relative to a fixed point.

I claim:—

1. In apparatus of the character described the combination, a movable support, an electro-magnet on said support including a pole piece and additional pole pieces arranged at the sides of the first pole piece, stationary magnetic members respectively arranged to be received between and in magnetically conductive relation to the first pole piece and one or the other of the second pole pieces, and armatures associated with the second pole pieces, substantially as and for the purposes set forth.

2. Apparatus as claimed in claim 1, wherein the stationary magnetic members are arranged in spaced pairs and at predetermined points throughout the path of movement of the movable support, substantially as and for the purposes set forth.

3. In apparatus for controlling the stopping of a lift at the top of floor landings in a well, the combination, an electro-magnet on the lift including a pole piece, additional pole pieces arranged at the sides of the first pole piece, and armatures associated with the second pole pieces and magnetic members arranged in spaced pairs adjacent each of the floor landings in the well and positioned to be received between and in magnetically conductive relation to the first pole piece and one or the other of the second pole pieces, substantially as and for the purposes set forth.

4. Apparatus as claimed in claim 3, wherein in a frame of non-conducting material is mounted on the lift for receiving the electro-magnet and its parts.

In testimony whereof I have signed my name to this specification.

JOHN BERTRAM MORTON KNUTSEN.
